UNITED STATES PATENT OFFICE.

JOHN H. STONEMETZ, OF MILLBURY, MASSACHUSETTS, ASSIGNOR TO THE STONEMETZ PRINTER'S MACHINERY COMPANY, OF SAME PLACE.

WEB-PRINTING MACHINE.

SPECIFICATION forming part of Letters Patent No. 429,873, dated June 10, 1890.

Application filed September 18, 1889. Serial No. 324,344. (No model.)

To all whom it may concern:

Be it known that I, JOHN H. STONEMETZ, a citizen of the United States, residing at Millbury, in the county of Worcester and State of Massachusetts, have invented certain new and useful Improvements in Web-Printing Machines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention consists in the improvements in web-printing presses hereinafter set forth and explained, and illustrated in the accompanying drawings, in which—

Figure 1 is a side elevation of my improved web-printing press and folders. Fig. 2 is a top or plan view of the same. Fig. 3 is a vertical longitudinal section view of the same on the line $x-x$ in Fig. 2. Fig. 4 is a horizontal longitudinal section view of the same on the line $y-y$ in Fig. 3, showing the arrangement of the paper-folding rollers.

Like letters of refer to like parts in all the figures.

In the construction of my improved printing-press shown, A is the frame of the machine. Upon this frame are mounted in stationary bearings type or plate cylinders B and B', which are connected with and are driven by a main driving-shaft C, by means of intermediate gears D D' d d'. Between and a little above the type-cylinders B and B' are impression or tympan cylinders E E', mounted in adjustable bearings e e' and geared to and driven by the type-cylinders B and B'. Centrally between the impression-cylinders E E', I mount cutting-cylinders F F' in adjustable bearings f f' in the upwardly-extending portion A' of the frame A and above the plane of the impression-cylinders E E', these cutting-cylinders F F' being geared together and driven by a gear G on the shaft of the cylinder E, which intermeshes with the gear G' on the shaft of the cutting-cylinder F. To the upper portion A' of the frame are secured arms H, which extend out

over the impression-cylinder E, the ends of which arms are provided with bearings h, adapted to receive the shaft a of a roll of paper b. Above and a little outside of the periphery of the cutting-cylinder F, I also mount in bearings g in the arm H a paper-conveying roller c. To the opposite side of the portion A' of the frame I also secure arms l, which extend out over the impression-cylinder E', in the ends of which arms are adjustable bearings l' in which a sheet-conveying roller i is mounted. On each end of the frame A, outside of and adjacent to the type-cylinders B and B', are mounted sliding carriages J, having ink-fountains J' therein. These carriages J are mounted and slide in ways on the frame A, and are actuated by means of shafts K, mounted in the frame A and having spur-gears k thereon, engaging with racks k' on the under side of the carriage J, the shafts K being also provided with hand-wheels K', by means whereof the carriages J can readily be moved back from the plate or type cylinders B and B', as shown by dotted lines in Fig. 1, to admit of the adjustment of the type-plates thereon. In the carriages J are mounted vibrating ink-distributing rollers L L' L², which are actuated by means of an intermediate gear-wheel M, which intermeshes with gears thereon and with the gear-wheels on the shafts of the type-cylinders B and B' when in position for operation, the cam mechanism for producing the vibrating movement of said rollers being of ordinary construction, a description thereof being deemed unnecessary.

The ink-feeding rollers l and l' are mounted in said carriages J, adjacent to the ink-fountain J', and are also actuated by cam-and-ratchet mechanism j j', connected with one of the vibrating distributing-rollers L', and is of the usual and ordinary construction.

Ink-distributing rollers m m m m and form-inking rollers n n n n are also mounted in the usual manner in suitable bearings in said carriages J, so that the entire inking apparatus may be simultaneously moved toward or away from the form-cylinders, as herein-after described.

Cylinders P P' are mounted in the frame

A, directly below the cutting-cylinders F F'. These cylinders P P' are placed a short distance apart and have on one side thereof ribs p p', which meet at each revolution of the cylinders P P', so as to nip the lower ends of the sheets passing down from the cutting-cylinders F F'. The cylinders P P' are geared together and one them P' is provided with a gear-wheel d, which operates as 5 an intermediate between the gear-wheel C' on the main driving-shaft C, and the intermediate gear D' geared together and to the cylinder P by means of a small intermediate gear o, these gears being shown in dotted 10 lines in Fig. 1. These gears are of such size that the breaking and switching cylinders P P' rotate at a slightly increased speed over and above the speed of the cutting-cylinders F F', so that when the lower end of the 15 partially-severed sheet is nipped between the ribs p p' on the cylinders P P', they, moving at a greater speed than the sheet is normally traveling, operate during the time the ribs p p' are in contact to suddenly accelerate the 20 movement of the down-coming sheet and break it away from the web above at the point at which the cutting-cylinders F F' have partially severed it.

In the frame A, directly below and adjacent to the cutting-cylinders F F', are mounted tape-conveying rollers N N', from which tapes run down to tape-rollers O O', immediately above and adjacent to the breaking and switching rollers P P'. These rollers 30 N and N' and O and O' are located a sufficient distance apart, so that a sheet will pass down freely between them. The rollers O O' are geared together and driven by a spur-gear, (not shown,) and from the roller O 35 endless tapes extend to and around the roller N, and from the roller O' like endless tapes extend to and around the roller N', so that the sheet travels downward by gravity between and guided by said tapes from the cutting-cylinders F F' to and between the switching and breaking cylinders P P' at a speed somewhat slower than that of said tapes until after it is nipped between the ribs p p' on the breaking-cylinders P P', and 40 severed from the web, as hereinbefore described, after which time it travels at the same speed of the tapes and breaking-cylinders P P'.

The breaking and switching cylinders P P' 45 are also provided with grippers r r', which are operated by ordinary gripper mechanism (not shown) to grip the lower edges of the sheets and lead them into the folders hereinafter described, the grippers r operating to 50 seize each alternate sheet and the grippers r' the other alternate sheets, the same being alternately released and conducted into the folders hereinafter referred to by means of a vibrating switch R, located partially between the cylinders P P', and operated in the usual manner by ordinary switch-actuating mechanism. (Not shown.)

In the ends of the lower part of the frame A, and below the plane of the breaking and switching cylinders P P', I place paper-folding machines Q Q' of the usual and ordinary construction of Stonemetz paper-folding machines. I have only shown the roller mechanism thereof, which is driven by means of the gears on the ends of the breaking and switching cylinders P P', which intermesh with gears on the shaft S of the folding-machine Q and the shaft S' of the folding-machine Q', the folding-rollers T, of said machines being geared thereto in the usual manner.

Centrally in the frame A below the plane of the folding-rollers of the folding-machines Q and Q', I mount a shaft U, having thereon a gear-wheel U', which intermeshes with the driving-gear on the main driving-shaft C and serves to actuate other portions of the mechanism (not shown) of the folding-machines Q Q'. It will be observed that the folding-machines Q and Q' are arranged with their inner ends close together, so that the one end of each of said folding-machines is directly under one of the breaking and switching cylinders and adapted to conveniently receive incoming sheets therefrom, so that each machine receives each alternate incoming sheet or pile of accumulated sheets discharged from said cylinders, they being directed into said folding-machines by the action of the vibrating switch R, or the grippers r r', hereinbefore referred to.

In operation a roll of paper b is placed upon the shaft a. The web passes down between the type-cylinder B, and the impression or tympan cylinder E, where the first side is printed, and thence up over the web-supporting rollers c and i, and down between the type-cylinder B', and the impression or tympan cylinder E', where the second side is printed, the web-supporting roller i being adjusted by means of the screws i', so as to cause the printed matter on the first side and on the second side of the web to register properly. The web then passes up around the impression-cylinder, and up over the cutting-cylinder F' and down between the cutting-cylinders F and F', when it is partially severed, whence it is conducted downward between the sheet-conveyer rollers N N' and O O', and conveyer-tapes to and between the breaking and switching cylinders P P', when the lower end of the sheet is nipped between the ribs p p' thereon and moved forward at an accelerated speed sufficiently to break the partially-severed sheet away from the web, whence it is directed into one or other of the folders Q and Q' by the operation of either of the grippers r or r' or of the vibrating switch R, as hereinbefore described.

Having thus fully described my invention, so as to enable others to construct and operate the same, what I claim as new, and desire to secure by Letters Patent of the United States, is—

1. In a web-printing press, the combination of a horizontal press-frame, type or form cylinders mounted in said frame near each end thereof, and impression or tympan cylinders mounted in said frame between said type or form cylinders, with cutting-cylinders mounted in said frame between the impression or tympan cylinders, and breaking and switching cylinders mounted in said press-frame below the cutting-cylinders, substantially as set forth. 5
2. In a web-printing press, the combination of a horizontal press-frame and cutting-cylinders mounted therein between the impression or tympan cylinders of the press, with breaking and switching cylinders rotating at a greater speed than that of said cutting-cylinders and longitudinal ribs on said breaking-cylinders adapted to nip the edge of a partially-severed sheet between them and break it from the web, substantially as set forth. 10
3. In a web-printing press, the combination of breaking and switching cylinders with grippers mounted on each of said cylinders, the grippers on one of said cylinders being adapted to close on each alternate sheet, and the grippers on the other of said cylinders being adapted to close on the other alternate sheet for directing said sheets alternately into the folders, substantially as set forth. 15
4. In a web-printing press, the combination of breaking and switching cylinders located on the same horizontal plane, with an oscillating switch between said cylinders adapted to direct alternate sheets from a vertical to a horizontal line of travel to the right and left alternately, substantially as set forth. 20
5. In a web-printing press, the combination of a horizontal press-frame having form-inking mechanism at each end thereof, type or form cylinders mounted in said frame next to the form-inking mechanism, and impression or tympan cylinders mounted in adjustable bearings in said frame between said type or form cylinders, with cutting and switching cylinders mounted centrally in said frame, and two or more paper-folding machines mounted side by side in said press-frame underneath the printing mechanism of the press, substantially as set forth. 25
6. The combination, in a web-printing press, of cutting-cylinders located in the upper part of the press-frame between the impression-cylinders thereof, breaking and switching cylinders located directly below the cutting-cylinders, with folding-machines located side by side below the breaking and switching cylinders, substantially as set forth. 30
7. In a web-printing press, the combination of the adjustable tympan or impression cylinders E E', and the adjustable cutting-cylinders F F', mounted in the projection A' of the press-frame, between and somewhat above the impression-cylinders E E', with the arms H, secured to the part A' of the press-frame for carrying a paper roll b and a web-supporting roll c, and the arms I, having an adjustable web-supporting roll i, mounted thereon, substantially as set forth. 35
8. In a web-printing press, the combination of a horizontal frame A, inking-mechanism carriages J and J' on each end of said frame, stationary type or form cylinders B and B', mounted in said frame next to the ink-carriages J and J', adjustable impression or tympan cylinders E and E', mounted in said frame between the type or form cylinders B and B', and cutting-cylinders mounted in said frame between the impression or tympan cylinders E and E', with breaking and switching cylinders P and P', and the paper-folding machines Q and Q', mounted in said press-frame under the printing and cutting mechanism of said press, substantially as set forth. 40
